UNITED STATES PATENT OFFICE.

ALLAN G. WOODFORD, OF JERSEY CITY, NEW JERSEY, ASSIGNOR TO
AMERICAN CIGAR COMPANY, OF NEW YORK, N. Y., A CORPORATION
OF NEW JERSEY.

MOLD-OPENING TOOL.

No. 817,829.

Specification of Letters Patent.

Patented April 17, 1906.

Application filed April 9, 1904. Serial No. 202,316.

To all whom it may concern:

Be it known that I, ALLAN G. WOODFORD, a citizen of the United States, residing at Jersey City, county of Hudson, and State of New Jersey, have invented certain new and useful Improvements in Mold-Opening Tools, fully described and represented in the following specification and the accompanying drawings, forming a part of the same.

10 This invention relates to certain improvements in tools for manipulating the parts of a separable mold.

Cigar-molds as now usually constructed consist of two parts, one part being provided 15 with receiving-sections for the bunches of cigars and the other part being provided with plunger-sections which are shaped to snugly fit into the receiving-sections when the two parts of the mold are in engagement. These 20 molds are so constructed that a very accurate fit exists between the plunger-sections and the receiving-sections, so that on account of the friction between the parts it is difficult to separate the parts of the mold 25 when it is desired to open the mold. Furthermore, after the mold has been opened and filled and the two parts of the mold are to be assembled it is desirable to bring the two parts together with an absolute accuracy of register, so as to avoid breaking the 30 walls of either the plunger or receiving sections, as would be the result if it were attempted to assemble the parts of the mold with the plunger-sections slightly out of 35 register with the cavities of the receiving-sections.

In the ordinary manipulation of these molds an empty mold is seized by the operator who prepares the bunches either by hand or by machine, and this operator pulls 40 the two parts of the mold away from each other, thus opening the mold, and after the mold is filled assembles the two parts by hand. The opening operation, as has been before pointed out, requires strength, and in 45 closing the mold unless the operator is careful to bring the plunger-sections into absolute register with the cavities of the receiving-sections the mold is apt to be broken when the two parts are forced together.

50 The object of this invention is to produce a tool for manipulating the parts of the mold by the use of which the opening operation is

more easily conducted, and when the mold is to be closed the two parts may be brought together so that the plunger-sections will be 55 in absolute register with the cavities of the receiving-sections.

With this and other objects in view the invention consists in certain constructions which will be hereinafter described and then 60 specifically pointed out in the claims hereunto appended.

In the accompanying drawings, which illustrate one embodiment of the invention, Figure 1 is a plan view of the tool with a mold therein, 65 the mold being shown as closed. Fig. 2 is a plan view of the construction shown in Fig. 1, the mold being shown as open. Fig. 3 is an end view of the construction shown in Fig. 1. Fig. 4 is a sectional view on the line 4-4 70 of Fig. 2, and Fig. 5 is a front elevation of the closed mold illustrated in Fig. 1.

In the drawings, the tool which forms the subject of the invention is shown as applied to a two-part mold of ordinary construction, 75 the plunger-carrying part of the mold being marked 1 and the part of the mold provided with receiving-sections for the bunches being marked 2. The tool consists of holders, one for each part of the mold, these holders being 80 constructed to receive and retain the parts of the mold. The holders are connected in such a manner as to permit one part of the mold to be moved away from the other part, this separation of the two parts of the mold, 85 however, being effected in such a way as not to disconnect the holders.

The specific means by which the holders are connected so as to permit the separation of the two parts of the mold without disconnecting the holders from each other may be varied within wide limits. Preferably, however, the holders will be pivoted together. The specific construction of the holders themselves may be also widely varied. As shown, 95 however, each holder comprises a pair of plates 3-4. Each of these plates is provided with arms 5, which preferably extend inwardly and upwardly from the arms. These arms are provided with openings or perforations through which pass bolts 6, these bolts forming pintles for the hinges. By carrying the arms inwardly and upwardly, as shown, 100 the two parts of the mold when the holder is

closed move nearly in a right line as the plunger-sections enter the receiving-sections on the other part.

When the holder embodies end plates, as described, holding devices will be provided which are arranged to engage each part of the mold. These holding devices may be varied widely in construction. As shown, however, each of the plates is provided with an angle-clip 7, these angle-clips being shewn as riveted to the plates and being arranged to engage the top and bottom of the parts of the mold. As shown, these clips are arranged to extend endwise into the space which is ordinarily left between the molds at the ends. While a single set of clips, such as 7, if properly arranged might be used to hold the parts of the mold, in the preferred construction and as shown these clips 7 are arranged to engage the parts of the mold near the inner corners, and a second set of clips is provided for engaging each part of the mold near the outer corners. In the preferred construction this second set of clips will be arranged to engage in the recess between the parts of the mold before referred to; but they will extend into this recess from the sides of the mold and not from the end. Preferably, also, this second set of clips will be arranged so as to be adjustable for different widths of mold. The particular construction by which these clips are caused to effect the functions referred to may be varied. In the construction shown, however, the plates 3 4 will be provided with slits 8, through which extend bolts 9, these bolts being connected to angle-irons 10. These angle-irons are in turn provided with angle-clips 11, which, as before stated, extend into the cavity between the ends of the mold and engage the top and bottom of each part of the mold.

In order that the mold may be snugly held in position, each of the plates 3 4 is preferably provided with a shoulder 12, against which one side of each part of the mold abuts, the other side of the mold resting against the angle-iron 10. By loosening the nuts on the bolts 9 the angle-irons carrying their clips may be moved toward and away from the shoulders 12, and thus the tool is adapted for use with molds of different sizes—that is to say, molds constructed for different lengths of cigars.

To provide for the ready insertion and removal of the molds, the plates 3 4 are spaced from each other a distance slightly greater than the length of the mold. The mold may therefore be inserted by shoving it between the clips on the plate 4, after which it is allowed to slide back between the clips on the plate 3, the clips on the plate 4 being of such a length as to permit this movement without becoming disengaged from the parts of the mold.

While the plates might be connected simply

by the hinge, in the preferred construction these plates will preferably be provided with a stiffening connection. While this stiffening connection may be of any suitable form, as shown one pair of plates 3 4 is connected by a flat strip 13, which is suitably bolted to the plates. The other set of plates 3 4 might be connected in the same manner, but as shown they are connected by means of a bowed rod 14, which is belted to the angle-iron 10 before referred to, this bowed rod forming a handle which assists in the ready manipulation of the tool.

The operation of the tool will be readily understood. After the mold has been inserted in the tool in the manner described the operator pulls the frames apart by the handle 14, the two parts of the mold being thus separated and being securely held between the shoulders 12 and the angle-plates 10, so that they do not shift out of register. After the mold has been filled the plates are swung together, the plunger-sections on the part 1 registering exactly with the receiving-cavities on the part 2, so that the parts of the mold take readily into engagement without danger of breaking the mold. The filled mold is then removed from the tool and another mold inserted therein.

Changes and variations may be made in the construction hereinbefore described, and illustrated in the accompanying drawings. The invention is not, therefore, to be limited to the exact construction shown and described.

What is claimed is—

1. A tool for manipulating the parts of separable bunch-molds, said tool comprising holders for the parts of the molds, the holders being constructed to permit the parts of the molds to be readily inserted and removed therefrom, and hinged connections between the holders, substantially as described.

2. A tool for manipulating the parts of separable bunch-molds, said tool comprising a pair of frames constructed to permit the parts of the mold to be readily inserted and removed therefrom, means on each frame for engaging and holding one of the parts of the mold, and hinged connections between the frames, substantially as described.

3. A tool for manipulating the parts of a separable bunch-mold, said tool comprising a pair of frames, adjustable means on each frame for engaging and holding one of the parts of the mold, and connections between the frames, said connections permitting the frames carrying the parts of the mold to be moved away from each other, substantially as described.

4. A tool for manipulating the parts of a separable bunch-mold, said tool comprising a pair of frames, adjustable means on each frame for engaging and holding one of the parts of the mold, and hinged connections

between the frames, substantially as described.

5. A tool for manipulating the parts of a separable bunch-mold, said tool comprising 5 holders for the parts of the mold, said holders being slightly longer than the length of the mold to permit the ready insertion and removal of the mold, and connections between the holders, said connections permitting the 10 frames carrying the parts of the mold to be moved away from each other, substantially as described.

6. A tool for manipulating the parts of a separable bunch-mold, said tool comprising 15 holders for the parts of the mold, said holders being slightly longer than the length of the mold to permit the ready insertion and removal of the mold, and hinged connections between the holders, substantially as described.

20 7. A tool for manipulating the parts of a separable bunch-mold, said tool comprising a pair of hinged frames each frame having two pairs of clips arranged to engage a part 25 of the mold and one of the clips of each pair being adjustable to permit the use of the tool with different sizes of molds, substantially as described.

8. A tool for manipulating the parts of a 30 separable bunch-mold, said tool comprising a pair of frames each frame being shouldered and provided with holding - clips whereby each part of the mold is held in position to register with the other part, and hinged 35 connections between the frames, substantially as described.

9. A tool for manipulating the parts of a

separable bunch-mold, said tool comprising a pair of frames, each frame being shouldered and provided with adjustable holding-clips 40 whereby each part of the mold is held in position to register with the other part, and hinged connections between the frames, substantially as described.

10. A tool for manipulating the parts of a 45 separable bunch-mold, said tool comprising a pair of hinged shouldered frames, the frames being slightly longer than the mold to permit the ready insertion and removal of the mold and each frame being provided with 50 adjustable clips to permit it to be employed with molds of different width, substantially as described.

11. A tool for manipulating the parts of a separable bunch-mold, said tool comprising 55 a pair of hinged frames, the ends of the frames being shouldered and each end of each frame carrying a stationary clip arranged to engage the upper and under side of each part of the mold, and an adjustable clip arranged 60 to engage the upper and under side of each mold, the ends of each frame being spaced from each other a distance slightly greater than the length of the mold so as to permit the ready insertion and removal of the mold, 65 substantially as described.

In testimony whereof I have hereunto set my hand in the presence of two subscribing witnesses.
